FLAP CONSTRUCTION

Edward F. Zaparka, Baltimore, Md., assignor to
 Zap Development Corporation, Baltimore, Md.,
 a corporation of Delaware

Application July 21, 1933, Serial No. 681,641
 Renewed January 19, 1937

8 Claims. (Cl. 244—42)

My invention relates to fluid supported devices, and more particularly to means for controlling the path of such devices.

I have illustrated the invention as applied to an airplane but it is to be understood that my special surfaces could be used for dirigibles as well as airplanes, and is applicable to vehicles which are fluid supported.

Heretofore, fluid supported vehicles have been controlled generally by movement of main control surfaces which take an angle to the path of travel of the vehicle. In the present instance I accomplish the control of the line of motion of the vehicle through fluid medium by means of auxiliary surfaces or obstructing devices which are supplemental to main control surfaces. The main control surfaces may move, or may not. In the drawings I have shown the main control surface as immobile, though it is contemplated that the main surface may move if desired.

An object of my invention is to provide a control surface for a fluid supported vehicle which will give quick maneuverability, is strong and sturdy in construction and easy of repair and replacement.

A further object of my invention is to provide a control surface for a fluid supporting vehicle to which the vehicle will quickly respond, thus giving a high degree of maneuverability and hence a large safety factor. This is of peculiar advantage in connection with aerodynamic devices, such as airplanes or dirigibles.

In the drawings:

Figure 1 is a side elevation of an airplane which has mounted upon it a combination stabilizer and elevator control, and a rudder control.

Fig. 2 is a top plan view of the airplane shown in Figure 1, parts being broken away to show the control mechanism in the cockpit.

Fig. 3 is a perspective view, partly schematic, showing the control mechanism for the stabilizer and elevators, the rudder mechanism being shown in dotted lines.

Fig. 4 is a detail view of the stabilizer mechanism taken in longitudinal section, parts being broken away to save space.

Fig. 5 is a sectional view taken along the line 5—5 of Figure 4, looking in the direction of the arrows.

Fig. 6 is a detail view of the hand wheel and worm gear for setting the stabilizer, taken along the line 6—6 of Figure 7, looking in the direction of the arrows;

Fig. 7 is a view of the mechanism shown in

Figure 6, taken along the line 7—7 of Figure 6, looking in the direction of the arrows;

Fig. 8 is a detail front elevation of the cam for adjusting the stabilizer and for operating the elevators;

Fig. 9 is a detail top plan view of the rudder mechanism.

In the drawings I have shown in Figure 1 an airplane having a fuselage 1, motor 2, and propeller 3. The plane is provided with wings 4 and 5 operated by aileron control rods 6. The ailerons are of the Zap type and have been covered in copending applications. Since this application relates to other control surfaces and their construction rather than to the ailerons per se, 15 the operative characteristics of the Zap aileron will not be enlarged upon.

The plane is provided with a rudder control main surface 7 and an elevator and stabilizer main control surface 8. The stabilizer and elevator control surface 8 has hinged at the rear portion thereof flaps 9 and 11 which are adapted to be rotated out into the airstream passing by the main surface 8, to either stabilize the airplane or to act as elevators and control its longitudinal 25 flight.

Likewise the main rudder surface 7 has mounted on either side thereof similar flaps 12 and 13 which are adapted to be rotated into the stream passing by the main rudder surface 7 to interfere with the flow around the main rudder surface 7, and to give desirable moments of force tending to move the tail of the airplane either to the right or left as desired.

Mounted in the cockpit is a pilot's seat 14, and in front of the seat is a foot pedal 15 for operating the rudder flap 12, and a foot pedal 16 for operating flap 13. These pedals may be constructed to be linked together by mechanism not shown, or a rudder bar may be used in place of the foot pedals 15 and 16. The mechanism as shown in the drawings for operating the rudder flaps 12 and 13 is provided with lost motion mechanism so that a rudder bar or foot pedals linked together may be employed. There is provided a control stick 17 which is pivoted to a block 18 mounted on a rod 19 which is supported upon two or more supports 21 on the floor of the cockpit (only one of the supports 21 is shown). Through the block 18 passes a pivot pin 22 which passes through two sides of a yoke 23, the upper end of which is attached to the control rod 17. The connections of the ailerons to the rod 19 for the lateral control of the ship through rotation of the rod 19 are not here given in detail, 55

as it is not thought necessary to do so to understand the present invention.

On the control rod 17 is mounted a block 24 which has pivoted at 25 a U support 26 (see Figures 2, 3, 6 and 7). The U support 26 is provided with upstanding ears 27 in which is pivoted a shaft 28. The shaft 28 has mounted on one end outside the space between the upstanding ears 27 a collar 29 which may be integrally formed with a hand wheel 31. On the shaft 28 and between the upstanding ears 27 is another collar 32, which is keyed to the shaft 28 as is the collar 29. The collar 32 is provided with worm threads 33 which are adapted to engage with a worm sector 34 which is keyed, as indicated at 35, to a tubular rod 36.

The worm sector is provided with a stop sector 37 which forbids the sector to rotate beyond the teeth provided thereon. The tubular rod 36 passes through and is journaled in the support 26 and a collar 38 is keyed to the rod 36 by pin 39 so that the worm sector 34 is held in place in engagement with the worm 33. This arrangement, as will be readily apparent, particularly from an inspection of Figures 6 and 7, permits rotation of the rod 36 through about 180°, but does not permit much greater rotation because of the stop member 37. The rod 36 terminates at its other end in gimbal joint 41 which permits the transmission of free rotational motion in a number of planes. The gimbal joint 41 is attached to a cam operating rod 42.

The cam operating rod 42 passes through a support plate 43 which may be welded, or otherwise suitably supported, to horizontal support tubes 44 and vertical support tubes 45, which in turn may be welded at the corners into longitudinal bracing members, or longerons, 46.

The plate 43 is apertured at approximately its middle and has welded into the aperture an annular journal member 47 which is provided with a friction bushing 48 in which the cam operating rod 42 is journaled, and is adapted to slide and also to rotate in response to the forces transmitted to it through the gimbal joint 41 by the rod 36, which is under the control of the pilot through control stick 17.

By movement of the control stick forward or backward rod 36, and hence cam control rod 42, may be made to reciprocate, as indicated in dotted lines, particularly in Figure 4. Through suitable adjustment of the hand wheel 31, the initial angular starting position from which the rod 36 may be reciprocated can be accurately controlled. As will now be explained, this will enable a stabilizer setting to be given to the stabilizing surface in the empennage of the airplane.

The rod 42 passes through the bushing 49 which is held in an annular journal support 51 which may be welded to a plate 52, which in turn can be welded to horizontal support tubes 53 and vertical support tubes 54. The horizontal support tubes 53 and the vertical supporting tubes 54 can also be welded to the longitudinal bracing tubes, or longerons, 46.

On that section of the cam operating rod 42 which lies between the plates 43 and 52 are provided cam surfaces. Reference is made particularly to Figures 3, 4 and 5, as well as to Figures 8 and 9, to show this cam surface construction. There is provided a cam sector 55 which has a conical face 56. Next to that is provided a middle cam section 57 whose configuration is shown partly in solid line and partly in

dotted line in Figures 8 and 5. There is a rear cam sector 58 having a conical surface 59 which is similar to the conical surface 56 of the cam sector 55 but angularly displaced therefrom 180°. The cam sector 55 is provided with a non-conical surface 61 and the cam sector 58 with a corresponding non-conical surface 62. This cam structure just described is keyed to move with the cam operating shaft 42. The raised portions of surface 57 are extended, one longitudinally 10 along 61, and the other longitudinally along 62; so that the trim will not be disturbed by longitudinal movement of the cam.

Adapted to bear against the cam surfaces described are roller members 63 and 64 which are mounted on stub shafts 65 and 66, respectively. The stub shafts 65 and 66 are reduced in diameter, as indicated at 67 (Figure 5) and are adapted to be secured by rivets or screws 68 to crank arms 69 which may be welded to tubular flap operating shafts 71, for the upper stabilizer and elevator flaps 11; or welded or otherwise attached to tubular shafts 72 for pivoting the lower stabilizer and elevator flaps 9. The shafts 71 are journaled in supports 73 which are provided with bushings 74. Journal supports 73 are suitably welded into plates 75. The shafts 72 are journaled in supports 76 provided with bushings 77. The journal supports 76 are also welded into plates 75.

The plates 75 are welded to vertical support tubes 78 (see Figs. 4 and 5). The vertical support tubes 78 are welded to the longerons 46.

The shafts 71 and 72 are journaled at their outer ends in suitable journal supports provided in the main stabilizer surfaces 8; such supports for the purpose of simplicity not being shown in detail. Keyed to the shaft 71 at 81 by welding, or other suitable means, are flanged support members 82 provided with horizontally disposed flanges 83 and vertically disposed flanges 84. Horizontally disposed flange members 83 of the flanged support members 82 may be riveted, as indicated at 85, to corrugated metallic bracing sheets 86, which in turn are suitably attached to outer corrugated metallic sheets 87 of the flap members 11.

Similarly the lower flap operating shafts 72, whose outer ends are also suitably journaled in the main stabilizer member 8, have attached to them at 88 flanged support members 89 provided with vertically disposed flanges 91 and horizontally disposed flanges 92. The horizontally disposed flanges 92 may be riveted, as indicated at 93, to corrugated bracing sheets 94 which are suitably attached as by rivets to outer corrugated metallic sheets 95 of the lower flaps 9.

Suitably attached to the vertically disposed flanges 84 of the flange supports 82, as indicated at 96, are springs 97 whose other ends are suitably attached to the internal construction at a point not shown in detail for the purpose of simplicity of description. Passing through the vertically disposed flanges 91 of the lower flaps 9 are pins 98, similar to the pins 96 for the upper flaps, to which are attached springs 99 whose other ends are attached to the same part of the bracing structure to which the springs 97 are attached. There may be a plurality of these springs for each set of flaps 11 and 9 on either side of the main stabilizer surface 8, (only one set of these springs is shown in Figure 3).

These springs which are attached to the interior of the flaps 11 and 9 tend to hold them in the closed position flush with the main sta-

bilizer surface 8, such position being indicated in Figure 1, in the detail perspective view of Figure 3, as well as in the views of Figures 4 and 5.

5 The operation of the stabilizer surfaces and of the longitudinal control, the construction of which has been described in detail, will now be given. Let us assume that for purposes of stabilization the ship is tail heavy and tends to 10 climb. In this case the hand wheel 31 is rotated so that the portion 57 of the cam surface assumes the position such as indicated in Figure 8 when the control stick 17 is held vertical. In Figure 8 it is shown that portion 57 of the cam 15 has a lower roller 64 which rotates the shafts 12 to lower the lower flap 9, thus tending to raise the tail. In Figure 8 the cam has been shown to be operated to its maximum extent, though it is to be understood that an intermediate position can be obtained by proper manipulation 20 of the hand wheel 31. Depending upon the degree that the flap 90 is lowered while the control stick 17 is in the vertical position, there will be a greater or less tendency for the tail 25 to be raised by the downward rotation of the flap 9. This tends to stabilize the ship.

If there is a tendency, however, for the tail 30 to rise through unbalance of the airplane, the hand wheel 31 can be rotated in the opposite direction so that the cam surface 57 will cause 35 the upward movement of the roller 63 when the control stick 17 is in vertical position, thus opening to the desired degree the flap 11, which will cause the fluid passing over the main control surface 8 to exert a force downward on the tail, tending to stabilize the airplane. It will be noted 40 that either the flap 9 or 11 can be opened when the stick is in the vertical position, but only one of them will be moved by this stabilizer control at one time.

The longitudinal control of the ship, other 45 than that provided with the stabilizer control just described, is accomplished by either pulling back on the control stick 17 or pushing forward 50 on it. Let us assume that the pilot pulls back on the control stick 17. In this case the roller 64 slides over the smooth horizontal surface 61 of the cam sector 55 and the lower flaps 9 are 55 not influenced by this backward movement of the control stick. The backward movement of the control stick, however, causes the shaft 42 to 60 be reciprocated towards the rear, as indicated by the dotted lines in Figure 4, and the roller 63 will climb the sloped surface 56 of the cam sector 55 which will cause the roller 63 to be moved 65 upwardly and the flaps 11 will be raised. This will push down on the tail of the airplane and cause the airplane to rise. A forward movement 70 of the control stick 17 will cause the roller 64 to be pushed downward by the sloped surface 59 of the sector 58, while the roller 63 travels in a horizontal path over the horizontal surface 62 of the cam sector 58. This will cause the flaps 9 to be lowered to raise the tail of the airplane.

75 The rod 19 leads to the aileron control which has not been described. The rotation of the rod 19 controls the aileron to give the desirable lateral control of the ship. Such lateral movement 70 of the control stick 17 to give the desired rotation of the rod 19 effects, to a certain extent, the rotation of the rod 36 and therefore of the rod 42, which will tend to rotate the cam surfaces just described. The cam surfaces and control linkages may be so designed that the rotation of the

cam surface does not affect the trim of the ship to an undesirable extent.

The longerons or longitudinal bracing tubes 46 terminate in a tail piece 100 to which they may be welded. The outline of the fuselage 1 is 5 indicated in dotted lines in the right hand end of the exploded view of Figure 9.

The rudder webs 13 and 12 in their closed position rest against a rear fin spar 101 (see Figure 9). The rudder flaps 13 and 12 are constructed 10 similarly to the elevator stabilizer flaps 11 and 9. The rudder flap 13 comprises a corrugated inner sheet metal section 102 which may be welded to a corrugated outer section 103 in which the corrugations run at substantially right angles to 15 the corrugations on 101. Attached to the inner corrugated sheet members 102 are flanged bracing or support members 104, provided with vertical flanges 105 which are welded or riveted to the inner corrugated sheet 102 of the flaps. 20 The flange bracing members are also provided with horizontal flanges 106. These flanged bracing members 104 are welded or otherwise suitably attached to rudder flap operating shafts, and are suitably spaced at intervals to give sufficient 25 bracing to the flaps 12 and 13. The flap 13, through the flange bracing members 104, is attached to a rudder flap operating shaft 107 and the flap 12 is similarly attached to a rudder flap operating shaft 108. 30

Welded, or otherwise suitably attached, to the longerons 46 are horizontal bracing tubes 109 to the upper one of which is welded a vertical bracing tube 111 for the rudder construction. Webs 112 are formed on the upper tube 109 and 35 support socket members 113 in which are adapted to rotate ends 114 of the flap operating shafts 107 and 108, which ends are of reduced diameter and are journaled in the socket members 113. The upper ends of flap operating shafts 107 and 40 108 are suitably journaled in the interior of the tail construction at points not shown.

Welded to shaft 108 are crank arms 115 which 45 carry pivot pin 116. Likewise welded to the shaft 107 are crank arms 117 which carry pivot pin 118. Adapted to lie between the crank arms 115 is a lost motion link 119 carried on the end of rudder operating rod 120. Similarly there is a lost motion link 121 which lies between crank arms 117 and fits over pivot pin 118. This lost 50 motion link 121 is carried by rudder operating rod 122. The rudder operating rod 120 is adapted to operate the flap 12, as is plainly apparent from Figures 2 and 3. The rudder operating rod 122 is adapted to rotate the flap 13. Each of the 55 rudder operating rods 120 and 122 are pivoted to foot pedals 15 and 16 respectively, as indicated in the side elevation of Figure 1 where the rod 122 is shown pivoted at 123 to the lever pedal 16, whose lower end is pivoted at 124 to a support 60 suitably attached near the floor of the fuselage.

In order to hold the flaps 12 and 13 in their inner position against the rear fin spar 101, I have provided springs 125, each of which has one end attached to each of the crank constructions 117 and 115 near their outer ends, as indicated in Figures 5, 9 and 4, and have their other ends attached to a loop provided in the approximate middle of the bracing tube 53. 65

The springs 125 tend to hold the flaps 12 and 13 70 in their nested position. Upon pushing on a foot pedal, however, the operating rod 122, or the operating rod 120, will be pulled forward, and through the engagements of the pivots 118 or 116 with their respective lost motion linkages 121 75

- or 119 either of the flaps may be moved into the outer position. Such position is indicated in dotted lines in Figure 9. The lost motion linkage connection just described is not necessary if a 5 rudder bar is not used, or if the foot pedals are not linked together by some linkage mechanism. Such linkage mechanism between the pedals is not shown and is common in the art.
- 10 By moving either flap to the outer position, i. e. into a position no longer approximately flush with the surface of the main rudder surface 107, forces are set up which tend to move the tail of the ship in a direction away from the outwardly moved flap. This gives simple, positive and sensitive steering control for the plane. Either flap 15 can be raised at will by pushing on the foot pedals. Where the foot pedals are not linked together, both flaps can be raised at once if desired, which, after the plane has been landed, may be used to retard the forward run of the airplane.

20 While I have shown and described the preferred embodiments of my invention, I wish it to be understood that I do not confine myself to the precise details of construction herein set forth 25 by way of illustration, as it is apparent that many changes and variations may be made therein, by those skilled in the art, without departing from the spirit of the invention, or exceeding the scope of the appended claims.

30 I claim:

1. A combined longitudinal control and stabilization mechanism for an airplane comprising superposed flaps, which are separately and pivotally mounted, and a single cam means operating the said flaps to effect stabilization and longitudinal control.

2. A combined longitudinal control and stabilization mechanism for an airplane comprising superposed flaps, which are separately and pivotally mounted, a single cam means to operate the said flaps to effect stabilization and longitudinal control, and means to set the cam to a desired point for purposes of stabilization.

3. A combined longitudinal control and stabilization mechanism for an airplane provided with a control stick, comprising split flaps, a single cam to operate the said flaps for purposes of longitudinal and stabilization control, said single cam being actuated by the control stick 45 by means of the movement of a shaft, for purposes of elevational control, and means whereby the shaft may be actuated independently of the control stick for purposes of stabilization.

4. A combined longitudinal control and stabi-

lization mechanism, for an airplane provided with a control stick, comprising split flaps, a single cam to operate the said flaps for purposes of longitudinal and stabilization control, said single cam being actuated by the control stick by 5 means of the movement of a shaft, for purposes of elevational control, and means mounted on the control stick whereby the shaft may be rotated independently of the control stick for purposes of stabilization.

10 5. A combined longitudinal and stabilization mechanism, for an airplane provided with a control stick, comprising split flaps, a single cam to operate said flaps for purposes of longitudinal and stabilization control, said single cam being 15 actuated by the movement of the control stick for purposes of elevational control, and means to actuate said single cam independently of the control stick for purposes of stabilization.

6. A combined longitudinal and stabilization 20 mechanism, for an airplane provided with a control stick, comprising superposed flaps, which are separately and pivotally mounted, a single cam to operate said flaps for purposes of longitudinal and stabilization control, said single cam being 25 actuated by the movement of the control stick for purposes of elevational control, and means to actuate said single cam independently of the control stick for purposes of stabilization.

7. A combined longitudinal control and stabilization mechanism, for an airplane provided with a control stick, comprising split flaps, a single cam to operate the said flaps, for purposes of longitudinal and stabilization control, said single cam being actuated by the control stick by means 30 of the movement of a shaft, means whereby the shaft may be actuated independently of the control stick for purposes of stabilization, and a second set of split flaps which are operated independently of the first set to effect longitudinal 35 rudder control.

8. A combined longitudinal control and stabilization mechanism, for an airplane provided with a control stick, comprising split flaps, a single cam to operate the said flaps, for purposes of 45 longitudinal and stabilization control, said single cam being actuated by the control stick by means of the movement of a shaft, means mounted on the control stick whereby the shaft may be actuated independently of the control stick for purposes of stabilization, and a second set of split flaps which are operated independently of the 50 first set to effect longitudinal rudder control.

EDWARD F. ZAPARKA.
